FIG. 7

FIG. 8

FIG. 9

FIG. 1 is a front elevation view of a disposable holder for a surgical knife blade showing the new design;
 FIG. 2 is a rear elevation view thereof;
 FIG. 3 is a top plan view thereof;
 FIG. 4 is a bottom plan view thereof;
 FIG. 5 is a left end elevation view thereof;
 FIG. 6 is a right end elevation view thereof;
 FIG. 7 is a perspective view thereof taken from above and to the left;
 FIG. 8 is a cross section taken on line 8-8 of FIG. 7; and
 FIG. 9 is a cross section taken on line 9-9 of FIG. 7. The broken lines representing the knife blade are shown for illustrative purposes only.

I claim:

The ornamental design for a disposable holder for surgical knife blade, as shown and described.
